ANGULARLY AND ROTATABLY ADJUSTABLE
WORK HOLDER AND SUPPORT THEREFORWilliam T. Berry, Jr., Bassett, Va., assignor to
Bassett Furniture Industries, Incorporated,
Bassett, Va., a corporation of Virginia

Application November 19, 1948, Serial No. 61,083

3 Claims. (Cl. 144—288)

1

This invention relates to a new and useful work holder and support therefor whose primary use is in conjunction with a conveyor system of the monorail type having suspended monorail trays carried by the monorail.

The object of this invention is to provide a work holder suitable for adjustable mounting on the vertical supporting framework of each monorail tray so that the work holder may be used to hold the work piece in a multiplicity of positions in order that work such as sanding, surface finishing, or decorating may be easily, quickly, and conveniently accomplished, and so that the work holder may be secured in a collapsed, out-of-the-way position when it is desirable to use the conveyor system only for the purpose of moving material on each tray along the conveyor.

More particularly, the invention provides a work holder and support therefor for use with a conveyor of the monorail type having a vertically disposed support suspended from the monorail with a horizontally supported conveyor tray carried by the support at its other end. On the vertically disposed support is fixed a vertical guide or slide and at the base of this support is a fixed pivot point having a linkage member such as a rod, bar, or strip pivoted therefrom. The other end of this rod is pivotally fixed to a mounting base preferably intermediate the ends thereof, the other end of the base adjacent the vertical support being connected to one end of a second rod. Secured to the other end of this second rod is a second bracket to which is secured a collar or slide block for adjustably cooperating with the heretofore mentioned vertical guide. On the mounting base is removably fixed a work piece holder which may hold a work piece in a plurality of positions in order that work of the type previously described may be accomplished.

In the drawings, wherein like numerals indicate the same part in each figure,

Figure 1 is a side view of the complete work holder, a work piece held by the holder, and a support therefor used in conjunction with a monorail conveyor system,

Figure 2 is a view similar to Figure 1 showing the work piece adjustably held in a horizontal position,

Figure 3 is a similar view showing the work piece removed and the work holder adjustably held in an out-of-the-way or collapsed position allowing the conveyor to be used for moving packing cases, etc.,

2

Figure 4 is an end view looking in from the right side of Figure 1,

Figure 5 is a top or plan view of the adjustable collar and pivot used in Figures 1—4 inclusive.

Figure 6 is a partial sectional side view of Figure 5,

Figure 7 is a sectional view of the adjustable feature of the work holder used in Figures 1—4 inclusive,

10 Figure 8 is an end view of Figure 7 showing the mounting of Figure 7 in conjunction with the mounting base and the removable work holder,

Figure 9 is a modification of Figure 7,

Figure 10 is a view through line 10—10 of Figure 9,

15 Figure 11 is a modification of Figure 5 and is a side view,

Figure 12 is a view taken through the line 12—12 of Figure 11,

20 Figure 13 is a view taken through the line 13—13 of Figure 11, and

Figure 14 is an end view of Figure 11 looking from the direction indicated by the arrow.

In order to more completely describe applicant's new and novel adjustable work holder and support therefor, reference will now be had to the drawings and in particular to Figures 1—4. An overhead monorail 1 of a conveyor system which is not shown in its entirety since it forms no part of this invention, has a vertical support indicated as a whole at 2 consisting of two diverging beams 3 depending from the monorail 1, as best shown in Figure 4, and a horizontally supported tray 4 held by the lower ends of the diverging supporting members 3, as shown in Figure 3. Fixed to and joining these two diverging beams are two transversely extending supporting or bracing members 5 and 6 which hold a vertically disposed or located guide 7. At the foot of the vertical support 2 adjacent the tray 4 are brackets forming pivot points 8 to which are pivotally connected a pair of supporting rods 9.

As shown, the brackets are mounted on the tray but they may be secured to the beams 3. The other end of these rods are pivotally connected at 10 to opposite sides of a mounting base 11, preferably intermediate the ends thereof. A single rod 12 is fixed at one end to the supporting base 11 in any suitable manner and pivotally held at its opposite end, as shown at 13, to an adjustable collar 14 adapted to have adjustable sliding movement on the guide 7.

45 With reference to Figures 5 and 6, it will be noted that the pivoted end of rod 12 is bifurcated 55 to form arms 13' which receive between them the

extension 15 on the collar 14. The arms 13' and extension 15 are pivotally connected by a lifting handle 16, the reduced end portion 17 of which extends through openings in the said arms 13' and extension 15 and has its free end threaded to receive the holding nut 18. The slide block or collar 14 has an opening 19 therein for slidably receiving the guide 7 and a transverse extension 20 therefrom which has an opening 21 extending into elongated opening 19. Within the transverse section 20 is slidably held a locking pin 22 having a detent 23 on one end thereof for cooperating with a series of aligned longitudinally spaced recesses located along the length of guide 7, one recess 24 only being shown. The pin 22 has a knob 25 fixed on the other end for disengaging the detent 23 which is normally held in a locked position by the compression spring 26 located about the pin 22 between the detent 23 and a flange shoulder 27 defined by the inner end of extension 20.

If desired, the locking device or adjustable ratchet of Figures 11-14, inclusive, may be used with sleeve 14 in place of the device shown in Figures 5 and 6. In Figures 11-14, inclusive, it is seen that bifurcated arms 28 extend from the collar 14 and pivotally retain the end of supporting member 12 between the arms by means of threaded bolt 29 and nut 30. Members 19-27, inclusive, correspond to like numbered parts of Figures 5 and 6. Also extending from collar 14 and extension 20 are two supporting flanges numbered 31 and 32 respectively, which pivotally support, by means of pin 33, a lifting handle 34, the lifting handle being fixed to the pin or dowel 33 for movement about the axis of the pin. A spring 35 attached at one end to a bracket 36 extending transversely from the lifting handle 34 and attached at the other end to a second bracket 37 normally holds the lifting handle 34 in an out-of-the-way position. However, when it is desirable to adjust the position of a work piece in a different position, the lifting handle 34 may be swung about its axis to a suitable or convenient lifting position.

One form of the removable adjustable work holder is shown in particular detail in Figure 8 and also in Figures 1-4, inclusive. On the top of the mounting base 11 are fixed two diverging angle irons forming a tapered keyway 38, the direction of the divergence being towards the fixed end of rod 12 in order to removably receive a cooperating wedge shaped plate 39 which has a vertically extending column 40 fixed vertically to it. The column 40 has a projecting flange or enlargement 41 forming a shoulder 41' for rotatably supporting a channel shaped supporting member 42 about a reduced round fixed extension 43 of column 40. On each end of channel 42 are fixed a pair of angle brackets 44 which support and hold a work piece such as tabletop 45 by means of screws 46 or other known fastening devices from the underside or unfinished surface. Fixed to the channel member 42 such as by welding is a ratchet block 47 having an opening 48 therethrough for cooperating with the reduced round fixed extension 43 of column 40.

In Figure 7 is seen one type of a ratchet locking device mounted in ratchet housing 47 for allowing selective swivel adjustment adjustable allocation of a work piece such as tabletop 45 about the axis of 43, housing 47 being part of the work holder. A hole 49 extends completely through the length of ratchet block 47 and meets hole 48 transversely. Within 49 are located two shafts 50, 75 base attached to the other end of said rod, a

each having a detent 51 for cooperating with recesses cut in extension 43. The shafts 50 are spring loaded by springs 53 which are about shafts 50 between detents 51 and rings 54 snapped into the ends of ratchet block 47 about shafts 50.

In Figures 9 and 10 is shown a second type of a selective adjustable ratchet locking device as used in ratchet housing 47. Within housing 47 is an opening 55 which is tapped at 56 at one end and which transversely meets at its other end opening 48. Within hole 55 is located a shaft 57 having at one end thereof a detent 58 for cooperating with a plurality of recesses 59 located about the circumference of extension 43 and similar to recesses 52 but of a less rounded nature. At the other end of shaft 57 is an externally threaded adjusting knob 60 which cooperates with threads 56 and rotatably holds shaft 57 in hole 56. A spring 62 is located about shaft 57 between detent 58 and the threaded adjusting knob 60 for holding detent 58 in a normally selected locked position in one of the recesses 59. By adjusting the position of knob 60, the compression of spring 62 is controlled thus allowing ratchet block 47 to be held non-rotatably in its selected position about the axis of column 40. A bolt 63 and washer 64 may be used to hold ratchet block 47 and hence the work piece 46 attached to block 47 in position by means of tapped hole 65.

This work holder and support therefor is particularly advantageous for use in a furniture factory. In such an industry it is desirable to have a work holder for use with a conveyor system which will allow the work piece to be moved along the line to various stations as finishing work is done on its surface. In finishing furniture surfaces it is desirable in such operations as sanding and applying stains and gloss finishes, to have the work piece supported so that all portions of it may be easily reached in both the horizontal and vertical positions in order to avoid, in particular, sags in the finishing material. Furthermore, it is desirable to be able to remove the work piece quickly in order that either other work pieces may be mounted for work thereon or in order for the support piece to be folded in an out-of-the-way position so that the conveyor system may be utilized for the handling of furniture or packing cases as shown in Figure 3, 66 being an example of an article carried by the conveyor. The unique way in which the device heretofore described accomplishes these operations is believed to be readily apparent and no further comments as to its operation are deemed necessary.

Although this device was developed in the furniture industry, it will be apparent to those skilled in the art that the support could easily be mounted on any supporting member, such as a wall, for use in many operations other than those carried out in the furniture industry where it is desirable to have an adjustable work holder and support therefor.

The terminology used in the specification is for the purpose of description and not of limitation, the scope of the invention being defined in the claims.

I claim:

1. An angularly and rotatably adjustable work holder and support therefor having a vertically disposed support adapted to be suspended at its upper end, said support including a vertical guide, an adjustable collar on said guide, a rod pivotally connected at one end to said collar, a supporting

70 base attached to the other end of said rod, a

second rod pivotally connected at one end to said base and pivotally connected at its other end adjacent the other end of the support, a tapered keyway mounted on said base, and a work holder received in said tapered keyway and having a part thereof mounted for rotation with respect to said base, said collar and said rods being movable to adjust the position of the base relative to said support.

2. An angularly and rotatably adjustable work holder and support therefor as set forth in claim 1, wherein said work holder comprises a wedge-shaped plate received in said tapered keyway, a column carried by said plate, and work holding means including means for rotating the same about the axis of said column.

3. An angularly and rotatably adjustable work holder and support therefor as set forth in claim 2, wherein means are provided for locking the work holding means to the column at various positions in its rotative movement.
